Primary Examiner — Ian Simmons*Assistant Examiner* — Shannon Morgan(74) *Attorney, Agent, or Firm* — Whitmyer IP Group LLC(57) **CLAIM**

The ornamental design for a medical imaging display screen or portion thereof with graphical user interface, as shown and described.

DESCRIPTION

The FIGURE is a front view of a medical imaging display screen or portion thereof with graphical user interface showing our new design.

The broken lines in the FIGURE showing a medical imaging display screen or portion thereof and graphical user interface represent portions that form no part of the claimed design.
